UNITED STATES PATENT OFFICE.

DAVID T. HELPRIN, OF NEW YORK, N. Y.

BINDER.

Application filed December 31, 1921. Serial No. 526,105.

To all whom it may concern:

Be it known that I, DAVID T. HELPRIN, a citizen of the United States, and a resident of the city of New York, borough of the Bronx, county of Bronx, and State of New York, have invented a new and Improved Binder, of which the following is a full, clear, and exact description.

The present invention relates to new and useful improvements in filing devices, and it pertains more particularly to a binder for securing loose leaves.

It is one of the objects of the invention to provide a new and improved form of binder, by means of which the loose leaves may be positively secured in operative position.

It is a further object of the invention to provide a new and improved form of binder especially adapted for use in carrying bill-heads or order blanks.

It is a further object of the invention to provide a new and improved form of binder especially adapted for making manifold copies; and so constructed that the separate sheets may be selectively removed from the binder.

It is a still further object of the invention to provide a new and improved form of binder in which a clamp is employed to maintain certain of the sheets in folded-over relation when desired.

With the above and other objects in view, reference is had to the accompanying drawings, in which

Figure 1 is a plan view of a binder constructed in accordance with the present invention, said binder being shown in open position;

Fig. 2 is a sectional view taken on the line 2—2 of Fig. 1, showing the rear wall of the binder in elevation;

Fig. 3 is a transverse sectional view of the binder;

Fig. 4 is a detail horizontal sectional view;

Fig. 5 is a detail side elevation;

Fig. 6 is a sectional view taken longitudinally of the binder mechanism on the line 6—6 of Fig. 4;

Fig. 7 is a modified form of the clamp.

Referring more particularly to the drawings, the binder in its preferred form comprises a pair of back members 10, hingedly secured together as indicated by the reference character 11, in any desired manner.

Secured to one of the back members 10 is a channel member 12, and said channel member 12 is secured in position by means of rivets or other suitable fastenings 13, which pass through one of the sides, the side carrying said rivets being extended beyond the other side, as indicated by the reference character 14. The opposite side of the channel member 12 has a depending flange portion 15, the purpose of which will be hereinafter more fully described. This channel member 12 is provided with two L slots 16 in the preferred form of the invention, and said L slots 16 are formed in the rear wall or base wall of the channel.

Pivottally secured to the outer end of the back 10 to which the channel is secured, by means of rivets or the like 17, is a plurality of plates 18, said plates being arranged in spaced relation one to the other. Each of these plates is provided with a projecting lug 19, and said lug is T-shaped and projects through its respective L-slot 16, as more clearly shown in Fig. 4. The projecting portion of each of these lugs is formed to provide an operating member which projects beyond the base of the channel 12. Interposed between each of the plates 18 and the bottom wall of the channel member 12, are coil springs 21; and said springs are adapted to exert an upward pressure upon their respective plates 18 and force the faces of the same toward the depending flange 15 formed on the top wall of the channel member 12.

Secured to the extended portion 14 of the channel member is a plurality of plates 25, and each of said plates 25 is notched or cut out as indicated by the reference character 26, to secure the springs 21 in place against accidental displacement relative to the plates 18 and the channel member 12, it being understood that the bottom convolution of each of said springs is of less diameter than the dimension of the opening 26 of the plates 25, by which construction said plates engage the bottom convolution of the springs to secure them in position.

The device functions in the following manner: The operating member formed by the T-shaped lugs 20 is depressed and when said plates 18 are thus depressed, the several sheets or leaves 30 are passed under the depending flange 15. Upon releasing the plates they are forced upwardly by the springs 21 and said leaves are clamped be-

tween the depending flange 15 and the plate 18 to secure the leaves in position.

When filling the device, if it is desired to maintain the plates 18 in depressed position 5 against the action of the springs 21, it is only necessary to shift the plates after they have been depressed, until the T-shaped member engages the portion 29 of the L-slot 16, the plates being rocked about their 10 pivotal point to permit of this action. After the leaves have been positioned, if the plates again be shifted until the T-shaped member may pass upwardly into the L-shaped slots, the plates will be caused to clamp the several 15 sheets or leaves in operative position.

In the present showing of the invention the device is adapted to contain a plurality of order blanks 35, and below said order blanks 35 is positioned a set of index cards

20 36. The binder which holds the index cards 36 has its plate 18 notched as at 37 in order that said plate may be engaged with and disengaged from posts 38 rigidly secured in the channel member 12. These posts are 25 necessary to maintain the index cards 36 against accidental displacement relative to the binder. To maintain the cards against accidental displacement they are notched to receive the posts 38.

30 In this application of the invention a clamp 40 is employed and said clamp is pivotally mounted as at 41 to the upper end of the upper face of the channel member 12, and it has one end 42 projecting beyond the end 35 of said channel member 12, as more clearly shown in Figures 1 and 2. Surrounding the pivot of this clamp is a coil spring 42 which serves to maintain the clamp in closed position under normal conditions.

40 In the use of this form of the invention, the order is written upon the top sheet and the end 42 of the clamp 40 is depressed, thus elevating the opposite end of the clamp. The top sheet is then folded over to the dotted line position shown in Fig. 1, after 45 which the carbon copies of the order may be removed upon a depression of the plate 18. After the carbon copies have been removed, they are properly filed between the index cards 36. It will be noted that the 50 bottom card of the index set is of greater length than the remainder of said set, and by this construction it will be apparent that as the order slips are placed within the index, it is only necessary to depress the 55 plate 18, when all of the slips filed between the index cards of the set may be withdrawn by a single operation owing to the fact that their ends project beyond the ends of the 60 index cards.

The reference character 50 designates a stop placed between two plates, and said stop has a vertically extending member 51, with which the sheets are adapted to engage 65 during the placement thereof to prevent the

sheets of one set overlapping those of the other set, thus causing confusion between the two sets. This stop is secured in place by means of a rivet or other suitable fastening 52.

70 In the modified form of the invention the channel member 12 has its end turned up as indicated by the reference character 60, and said end is cut as at 61, to provide two parallel ears 62. In this form of the invention the clamp 40 is provided with depending portions 63, by means of which it is pivoted as at 64 to the ears 62.

75 While in the present instance the device has been shown with two plates 18 and as a double binder, it is obvious that the same can be made in either single or multiple form without departing from the spirit of the invention.

80 What is claimed is:

85 1. A binder comprising a base, a channel member carried by the base, a plate pivotally mounted to the base and having a T-shaped projection extending through a portion of said channel member, and means for 90 maintaining said plate in engagement with one side of said channel member to maintain a plurality of loose leaves in position on said plate.

95 2. In a binder, a base, a channel member secured thereto and provided with a notch, a plate pivotally mounted on said base and having a T-shaped projection extending through the notch of the channel member and forming an operating member, and 100 means interposed between the plate and a portion of the channel member to maintain said plate in engagement with one of the edges of the channel member to secure a plurality of loose leaves between the plate and 105 the channel member, substantially as described.

110 3. A binder comprising a base, a channel member having an L-shaped slot, said channel member being secured to said base, a 115 plate pivotally mounted at one end to the base, a projection on the other end of said plate, said projection extending through the L-shaped slot of the channel member and adapted to move laterally to maintain the 115 plate in depressed position, and resilient means interposed between one of the walls of the channel member and said plate to normally press the plate upwardly, as and for the purpose set forth.

120 4. In a binder, a base, a plate pivotally secured thereto, a channel member rigidly secured to the base and overlying a portion of said plate, resilient means for forcing said plate in the direction of one of the 125 walls of the channel member to clamp a plurality of leaves therebetween, means for guiding the pivoted plate in its movement toward the base, and means for maintaining the pivoted plate in depressed position.

5. In a binder, a base, a plate pivotally secured thereto, a channel member rigidly carried by the base, means interposed between one of the walls of the channel member and said plate to normally force said plate in the direction of the other wall of the channel member to clamp a plurality of sheets between said plate and one of the walls of the channel member, and a pivoted clamp carried by the channel member for holding said sheets when turned over upon said channel member.
6. In a binder, a base, a channel member rigidly secured thereto, a plate pivotally secured to the base and having a projection extending through a slot in one of the walls of the channel member, resilient means interposed between one of the walls of the channel member and said plate to normally force said plate in the direction of one of the walls of the channel member, and means for maintaining said plate depressed and in spaced relation with the last-mentioned wall of the channel member against the action of said resilient means.
7. In a binder, a base, a channel member extending approximately throughout the length of the width of said base and rigidly secured thereto, said channel member having a plurality of slots, a plurality of plates pivotally carried by the base, a projection on each of said plates extending through its respective slot in the channel member, means for exerting pressure on said plates and forcing them normally in the direction of one of the walls of said channel member, and a spacing guide mounted between said plates and rigidly carried by the base, as and for the purpose set forth.

DAVID T. HELPRIN.
